G. E. THACKRAY,
MINE CAR.
APPLICATION FILED AUG. 15, 1921.

1,414,056.

Patented Apr. 25, 1922.

Inventor

Geo. E. Thackray

UNITED STATES PATENT OFFICE.

GEORGE E. THACKRAY, OF WESTMONT BOROUGH, PENNSYLVANIA.

MINE CAR.

1,414,056.

Specification of Letters Patent. Patented Apr. 25, 1922.

Application filed August 15, 1921. Serial No. 492,338.

To all whom it may concern:

Be it known that I, GEORGE E. THACKRAY, a citizen of the United States, and a resident of the borough of Westmont, county of Cambria, and State of Pennsylvania, have invented certain new and useful Improvements in Mine Cars; and I do hereby declare the following to be a full, clear, and exact description of the invention, such as will enable others skilled in the art to which it appertains to make and use the same.

My invention relates to cars which may be used in coal mines or other mineral mines, on industrial railways or in manufacturing plants and which are particularly adapted for hauling bulk material and especially useful when made into trains, as my construction and strengthening of the car sills and bumpers thereof adapts them to readily withstand the pulling and buffing stresses to which they are subjected.

The car body is preferably made of metal sheet or plate pressed into form, and for ease and simplicity of construction the bottom of the car is preferably made substantially flat, the sides extending upwardly for a short distance and then flared outwardly therefrom in order to provide greater capacity for lading, particularly when used in mines where the head room is limited. The upper edges of the car sides are preferably provided with a rounded bead formed integral therewith in order to strengthen and stiffen them, and the car ends may be made of flanged plates secured and riveted to the side and bottom portions.

In certain cases one or both of the car ends may be hinged so that the car may be dumped endwise, but I prefer to make the car ends fixed and riveted or bolted to the other portions as these latter are stronger and simpler, and well adapted for dumping in what is known as a rotary dump of any of the various types now used in connection with coal and other mines.

One of the particular features of my invention resides in securing a heavy timber, preferably oak or other strong timber, to the inside of the car bottom extending centrally and longitudinally thereof with ends projecting outwardly therefrom.

This timber sill is secured to the inside of the car bottom by means of metal straps passing over its end and center portion and otherwise if desired, and through bolts or

rivets are passed through the car bottom, the timber sill and the intermediate portion of the strap for further securing the timber to the car.

On account of the necessarily small thickness of the metal plate or sheet, the car body is not best adapted to withstand the excessive buffing stresses or pulling stresses, but is primarily designed as a container for the lading. The introduction therein of the heavy wooden sill makes the structure very well adapted to withstand the buffing stresses and pulling stresses on account of the large area of the wooden sill, which reduces the unit stresses therein, beside which wood has a certain amount of elasticity, but the modulus of elasticity is much lower than steel and it also has certain shock absorbing qualities and the reaction after a shock is not so energetic as that of steel, so that the wooden sill is very effective and useful in such cases.

The ends of the center sill are provided with bumpers, which may be of various styles adapted to receive the buffing stresses and transmit same to the sill, and I may also provide a longitudinal continuous metal draw bar extending through the car and secured thereto and to the bumpers, the ends of this draw bar being bent upwardly and provided with holes to receive the coupling pins in connection with corresponding holes in the bumper.

When cars of this kind are formed into trains their construction is such that they have a continuous and strong center sill and a continuous draw bar so that the pulling stresses do not affect the car body, but are concentrated in the center sill and draw bar, while the buffing stresses, which are frequently quite severe owing to the movement of the cars when they contact forcibly with each other, are adapted to be received and absorbed by the wooden center sills, which, on account of their size and character of material, receive such shocks and absorb them without damage, resulting in preserving the car and its body, which otherwise might be bent or distorted by such shocks.

Having thus given a general description of my invention, I will now, in order to make the matter more clear, refer to the annexed sheet of drawings, which forms part of this specification, and in which like characters refer to like parts:

Figure 1 is a top plan view of my improved mine car; Figure 2 is a side elevation of the car with the left hand portion shown in vertical sectional elevation on the longitudinal center line of the car; Figure 3 is a vertical transverse sectional elevation taken on the line III—III of Figure 2, and Figure 4 is a cross sectional elevation through my timber center sill and adjacent parts showing a continuous draw bar mounted above the straps which secure the sill to the car body instead of inside or below said straps as illustrated in Figure 3, the construction of Figure 4 being the preferable design, as it allows the draw bar to be placed or removed without interfering with the other portions.

Referring now to the characters of reference on the drawings; 1 indicates the car in general; 2 the side portions thereof and 3 is the car bottom, these being formed integral from a plate or sheet of metal by pressing or otherwise; 5 is a wooden center sill which is secured to the top of and central with the car bottom and is secured and held in place by the bent plates 4, shown with outstanding ends, riveted or bolted to the car bottom. I may also provide strengthening or reinforcing angles 6 on the car bottom, but these may be omitted if desired. The car bottom is preferably provided with reinforcing plates 7 attached to the upper side of the bottom to serve as washers or reinforcements for attachment of the axle bearings thereto by means of the bolts 9. 10 is a continuous draw bar composed of a flat rectangular bar of iron or steel and 11 are bolts which pass through the draw bar 10, the center sill 5, the car bottom 3 and the reinforcing plates, including the central reinforcement 8 or the angles 6 for the purpose of securing the sill firmly to the car. The draw bar 10 is provided with bent-up ends 12 as illustrated, adapted to receive the coupling links between said ends and the bumpers as illustrated at the left hand side of Figure 2. Through bolts 13 are provided which pass through the ends of the continuous draw bar 10, the center sill 5 and portions of the bumper in order to secure all these parts firmly together near the ends where the shocks of use are most severe. The ends of the car are 14, which are preferably formed of flanged metal and riveted to the car sides and bottom as illustrated. On the end projections of the sills 5 are mounted the buffer blocks 17, which may be of pressed or cast metal adapted to surround the ends of the sill 5 and provided with lugs or ears 15 extending laterally thereof and secured to the other parts of the end of the car by the bolts 16, thus adding to the strength and rigidity of the end construction to absorb or resist the shocks to which it is subjected. The buffering end of

the buffers are 18, adapted, on adjacent cars, to contact with each other when the cars come together and to first resist the buffering shocks and transmit them to the wooden center sills 5, the buffer blocks each being further provided with a bottom flange 19 below the wooden center sill and the upper flange 20. The ends of the continuous draw bar 10 are provided with coupling pin openings 21 and the buffer blocks are similarly provided with registering holes 22 adapted to receive the coupling pins 23, the buffer block being further provided with an upwardly extending portion 24, which serves as a separator between the upwardly bent ends 12 of the draw bar and the other portions of the construction immediately below same, these parts being secured together by the bolts 13 as previously explained. 25 are transverse reinforcing bars which extend crosswise of the car ends in order to strengthen and stiffen the same and secured to the other parts by bolts or rivets.

Although I have described and illustrated my invention in considerable detail, I do not wish to be limited to the exact and specific details thereof as shown and described, but may use such modifications in substitutions for, or equivalents thereof as are embraced within the scope of my invention or as pointed out in the claims.

Having thus described my invention, what I claim and desire to secure by Letters Patent is:

1. A metal car body having a substantially flat bottom and a wooden longitudinal center sill mounted thereon and secured thereto.
2. A metal car body having a flat bottom, a wooden center sill mounted and secured thereon, its ends projecting outwardly from the car body and provided with buffer and coupling means.
3. A car body composed of metal plate with a flat bottom, a wooden center sill mounted thereon, and a plurality of metal straps partially surrounding said center sill and secured to the car bottom.
4. In a car body, having a flat metal floor, a wooden center sill mounted thereon and secured thereto by metal straps secured to the car body and to the sill and body by through bolts.
5. In a metal car provided with a flat bottom, a wooden center sill mounted thereon, its ends projecting outwardly therefrom, said center sill being secured to said car bottom by metal straps and through bolts, in connection with a continuous draw bar mounted on and above said center sill and with its ends spaced apart therefrom.
6. A metal car provided with a flat bottom, a wooden center sill mounted thereon and extending longitudinally thereof with its ends projecting outwardly therefrom, metal bumpers mounted upon the ends of

said center sill, a continuous draw bar also mounted on and above the same with its end portions spaced apart therefrom and with registering coupling pin holes in said draw bar, bumper and center sill.

7. A metal car provided with a flat bottom, a wooden center sill mounted thereon with its ends extending therefrom, a continuous draw bar mounted on said center sill with its ends spaced apart therefrom, metal straps surrounding the upper and side portions of said center sill secured thereto and to the car body, and a draw bar with upwardly projecting ends secured to the car,

and bumpers mounted on the ends of said center sill.

8. A metal car body provided with a flat bottom, a wooden center sill mounted centrally and extending longitudinally thereof and secured thereto by means of straps secured to the car body and passing over the same, bolts through the sill, the straps, and the car body, the outwardly projecting portions of said sill being provided with buffer and coupling means.

In witness whereof I hereunto affix my signature.

GEORGE E. THACKRAY.
